Lutrelle P. Wassmann, Chicago, Ill., assignor to
General Electric Company, a corporation of
New York

Application July 29, 1952, Serial No. 20,795

Term of patent 14 years

(Cl. D67—3)

To all whom it may concern:

Be it known that I, Lutrelle Paul Wassmann, a citizen of the United States, residing at Chicago, in the county of Cook and State of Illinois, have invented a new, original, and ornamental Design for an Evaporator Door for Refrigerators or the like, of which the following is a specification, reference being had to the accompanying drawing, forming a part thereof.

Fig. 1 is a front view of an evaporator door for refrigerators or the like embodying my new design.

Fig. 2 is an enlarged sectional view thereof taken on lines 2—2 of Figure 1.

I claim:

The ornamental design for an evaporator door for refrigerators or the like, substantially as shown.

LUTRELLE PAUL WASSMANN.
